ARTICLE POSITIONING AND CASE LOADING APPARATUS

John L. Ferguson, Jr., Downers Grove, Ill., and Wayne E. Gary, Reading, Pa., assignors to Textile Machine Works, Wyomissing, Pa., a corporation of Pennsylvania
Filed Nov. 10, 1961, Ser. No. 151,492
13 Claims. (Cl. 53—61)

The instant invention relates to a machine for loading products such as cans into rectangular cartons or cases and more particularly is concerned with a machine for automatically packaging cans of the type each having a bail or handle consisting of a wire loop with its ends received in ears projecting from diametrically opposite sides of the can adjacent the upper end thereof. Such cans are typified by gallon paint cans which are normally packaged for shipment with four to a carton or case but it will be understood that the invention is not so limited and that cans of other types, sizes, and for other purposes may be encased by the device of the instant invention.

Bailed cans of the type referred to, as they are discharged in procession from the filling, lidding, and bail applying stations, normally are in no particular or defined arrangement with respect to positions of the bails thereon the vertical planes of the bail ears lying at any angle with respect to the direction of movement of the succession, and the bails themselves resting against one or the other of the sides of the can or being in raised or partially raised position. These conditions add to the operations necessary to package the cans as, unless an oversize carton is to be used which is obviously undesirable, the bails must be brought against the can walls and the cans so arranged that when in the case or carton the bail ears and the portions of the bails projecting outwardly therefrom lie in the open spaces defined by the divergence of the can and carton walls. Heretofore to so position the bails and arrange the cans has necessarily required manual operations.

The principal object of the instant invention is the provision of apparatus adapted to receive boiled cans and to automatically arrange the cans in groups constituting case loads with the bail and bail ears of each can of a group in the desired positions described above. Another object of the invention is the provision of means for loading such groups of cans into cases while maintaining the bails in their predetermined set positions whereby in the package the loops of the bails resting against the can walls engage the walls of the case with the bail ears and projecting bail portions lying in open spaces of the carton or case.

Another object of the invention is the provision in apparatus attaining the foregoing objects of means for receiving the cans, shunting the cans into separate lanes, moving the cans through said lanes, and first rotating the cans to align the bail ears transversely to the direction of travel of the cans.

Another object of the invention is the provision in such apparatus of means for positioning the bail of each can of a group of four cans against the can wall defining in part the front or rear of the group.

A further object of the invention is the provision in such apparatus of means for segregating each such group of cans to be encased from following cans or groups thereof. A still further object is the provision of means to rotate each can of a segregated group to an extent that the vertical plane of the bail ears extends across a corner of the group.

A still further object of the invention is the provision in such apparatus of means for loading groups of cans in the positions defined in the last mentioned object into

2

cases or cartons while maintaining the relative positions of the cans of each group.

A still further object of the invention is the provision of means for driving the several mechanisms referred to above to obtain a predetermined sequence of operations.

The invention will be more fully understood and further objects and advantages thereof will become apparent when reference is made to the more detailed description to follow and to the accompanying drawings in which:

FIG. 1 is a top plan schematic view of the apparatus employed in the instant invention together with certain associated mechanisms;

FIG. 2 is a diagrammatic plan view of a carton loaded by the apparatus of FIG. 1 disclosing the arrangement of the cans therein;

FIG. 3 is an elevational view on an enlarged scale taken in the direction of the arrows 3—3 of FIG. 1;

FIG. 4 is a top plan view on a further enlarged scale of the portion of the apparatus between the arrows 4—4 of FIG. 3;

FIG. 5 is an enlarged elevational view of a portion of the mechanism shown in FIG. 3;

FIG. 6 is an enlarged elevational view of a portion of the mechanism between the arrows 6—6 of FIG. 4;

FIG. 7 is a detailed cross-sectional view on an enlarged scale taken on the line 7—7 of FIG. 3 in the direction indicated by the arrows;

FIG. 8 is a detailed plan view of the portion of the mechanism between the arrows 8—8 of FIG. 6;

FIG. 9 is an enlarged cross-sectional view taken on the line 9—9 of FIG. 5 in the direction indicated by the arrows;

FIGS. 10 to 10-d inclusive are cross-sectional views taken on the line 10—10 of FIG. 5 looking in the direction indicated by the arrows and illustrating the parts during different stages of their operation;

FIG. 11 is a cross-sectional view taken on the line 11—11 of FIG. 5 looking in the direction indicated by the arrows;

FIG. 12 is a cross-sectional view on an enlarged scale taken on the line 12—12 of FIG. 1 looking in the direction indicated by the arrows;

FIG. 13 is a sectional view on an enlarged scale taken on the line 13—13 of FIG. 12 looking in the direction indicated by the arrows;

FIG. 14 is a sectional view on an enlarged scale taken on line 14—14 of FIG. 12 looking in the direction indicated by the arrows;

FIG. 15 is a detailed elevational view on an enlarged scale of a portion of the mechanism of FIG. 12;

FIG. 16 is an enlarged detailed plan view of the portion of the mechanism between the arrows 16—16 of FIG. 15;

FIG. 17 is an enlarged elevational view taken in the direction of the arrows 17—17 of FIG. 12;

FIG. 18 is a cross-sectional view taken on the line 18—18 of FIG. 17 looking in the direction indicated by the arrows;

FIG. 19 is an enlarged detailed elevational view of a portion of the mechanism of FIG. 12;

FIG. 20 is an enlarged sectional view taken on the line 20—20 of FIG. 12 looking in the direction indicated by the arrows;

FIG. 21 is an enlarged sectional view taken on the line 21—21 of FIG. 20 looking in the direction indicated by the arrows;

FIG. 22 is an elevational view, with parts in section of the mechanism shown in FIG. 20 looking from the left thereof;

FIG. 23 is an enlarged top plan view of the portion of the apparatus between the arrows 23—23 of FIG. 12;

FIG. 24 is an enlarged sectional view taken on the line 24—24 of FIG. 23 looking in the direction of the arrows;

FIG. 25 is an enlarged plan view of the clutch mechanism of the apparatus shown in FIG. 12;

FIG. 26 is a sectional view taken on the line 26—26 of FIG. 25 looking in the direction indicated by the arrows; and

FIG. 27 is a detailed elevational view with parts in section of the mechanism shown between the arrows 27—27 of FIG. 25.

Referring now to the drawings and particularly to the schematic showing in FIG. 1 there is illustrated an apparatus in accordance with the invention. Also illustrated in said figure are additional mechanisms, particularly a case opener, indicated generally at 30, and a case sealing and pressing unit, indicated generally at 32, which form no part of the instant invention and which may be of any suitable type. Hence they will not be described in detail. The device of the instant invention includes a continuously driven conveyor 34 adapted to receive at its entry end (the left end as viewed in FIG. 1) cans to be packaged or encased after filling, lidding, bail applying, etc. The cans 36, such as gallon cans of paint having bail ears 37 and bails 38 with their ends received within perforations in the bail ears, are delivered to conveyor 34 without predetermined orientation of the bails. As will be understood the bails in some instances may be resting against one side or the other of the can and in other instances may be more or less upright. Also the cans may be in any position laterally of the conveyor. A dividing wall 40 defines, in the particular construction illustrated, two channels through which the cans are conveyed, the channels being of a width approximately equal to the diameters of the bodies of the cans. At the forward end of the dividing wall, the left end as viewed in FIG. 4, a switching device 41 is pivotally mounted, the switching device functioning to shift the cans received on the conveyor alternately into the channels. As illustrated particularly in FIG. 4 switching device 41 comprises a substantially triangular plate mounted for pivotal movement on a stud 42 threaded into dividing wall 40, the extent of its pivotal movement in either direction being under the control of a stop 43 also secured to the dividing wall. As will be readily understood the switching device, when in either the full or dot-and-dash line position illustrated, will block one of the channels causing a can to enter the other channel. Upon entry of the can and its continued movement down the other channel the can will cause the switching device to rotate on its pivot, as for example from the dot-and-dash line position of FIG. 4 to the full line position, to block the other channel and open the one channel to the next succeeding can.

As the cans travel along the channels they first pass through a bail ear orienting station indicated in its entirety at 45, and hereinafter to be described in detail, in which the cans are rotated to position their bail ears in planes transversely of the conveyor. Continued travel of the conveyor carries the cans to what is here termed a "bail flipping station" indicated generally at 46, and also to be described in detail hereinafter, in which the cans of a group of cans to constitute a case load, four in the instance illustrated, are subjected to the action of means to flip their bails from whatever position in which they lie into positions wherein the bails of the leading two cans of the group lie against the forward walls and the bails of the trailing two cans lie against the rearward walls thereof.

Conveyor 34 then delivers the cans to a can assembling orienting and loading station indicated generally at 47 wherein cans constituting a case load and with their

bails in the positions determined by the bail flipping means are removed from conveyor 34 assembled in a group and the group separated from following cans. The cans of the assembled group are then individually rotated through arcs of approximately forty-five degrees to position the planes of their bail ears diagonally with respect to the group, which will be their positions when encased (FIG. 2), and the group is subjected to the action of a plunger mechanism 48 by which the group is impelled laterally into a case or carton 50 previously opened at the case opening station 30 and brought into alignment with the pusher member. As will be observed the cases are of the end or side opening type whereby the cans will stand upright in the final package. Thereafter the loaded cases are conveyed to the case flap sealing and compressing station of any desired type indicated at 32 wherein glue is applied to the flaps and the flaps are closed and sealed.

As previously mentioned the cans when loaded in the manner described above have their bails resting against the sides of the cans in the positions as illustrated in FIG. 2 with the bail ears in the open spaces formed by the divergence of the cans and the case walls. Hence the bail ears and the portion of the bails projecting outwardly therefrom do not press against the case walls permitting the cans to be tightly packed without distortion or injury to the case.

The several mechanisms in accordance with the instant invention and by which the foregoing operations are carried out will now be described in detail.

Referring particularly to FIGS. 3, 4 and 6 to 9 inclusive conveyor 34 comprises a pair of endless belts 52 positioned at opposite sides of the dividing wall 40, the latter being mounted in the machine to extend upwardly between the belts. The belts as illustrated in FIG. 3 are carried by rollers 53 (only the rollers at the left end of the conveyor being shown in that figure) fixedly mounted on suitable shafts 58 which are in turn mounted for rotation in bearings 54 supported on frame members 55 on opposite sides of the machine. The upper flight of each belt is held against downward yielding by a plate 56 (see FIG. 7) resting upon and secured to the upper edge of one or the other frame member 55. Plates 56 at the outer edges carry angles 57 secured thereto in any suitable manner, the vertical flanges thereof defining the outer walls of the two conveying channels hereinabove referred to. The width of the channels, i.e. the spacing of the flanges of angles 57 from the adjacent sides of dividing wall 40 is such that the cans can move freely through the channels with slight clearance. It should be noted that the height of the dividing wall as well as of the flanges of the angles 57 is such that neither will contact the bails or bail ears of the cans. The belts are continuously driven to cause the upper flights thereof to travel in the direction indicated by the arrow (FIG. 1) and at a predetermined uniform speed by a motor 85 through the medium of a line shaft 86 and a suitable gear box and belt drive connected to the shaft 58 at the right end of the conveyor indicated generally at 87 in FIG. 3.

Mounted adjacent the outer edges of the conveyor at the bail ear orienting station 45 and associated with each of the belts 52 of the conveyor are means to rotate the cans and secure the transverse orientation of the bail ears previously referred to. Inasmuch as the can rotating means associated with the belts are substantially identical or mirror images only one will be described, namely, the one nearest the viewer in the showing of FIG. 1. Each can rotating means comprises an endless belt 60 provided with a gripping, can engaging surface as by grooving the same as illustrated at 61 in FIG. 6. Belt 60 is positioned at a level to contact the can wall adjacent the lower portion thereof and beneath the bail in any position of the latter, and is carried by pulleys or rollers 62. Roller 62 at the left as viewed in FIG. 6 is mounted for rotation on a vertically extending stub shaft 64 carried by a bracket

65 from side frame member 55. Roller 62 at the opposite end of the belt, as viewed in FIG. 6, is mounted for rotation with a vertically extending shaft 66 which in turn is mounted for rotation in bearings 67 secured to frame member 55. Each shaft 66 is constantly rotated from line shaft 86 through suitable gearing indicated generally at 88 to cause continuous travel of the associated belt at a speed substantially greater than, and with its inner flight moving in the same direction as, the upper flight of conveyor belt 52. Rollers 62 are positioned with respect to the lateral extent of the conveyor belt 52 to place the inner flight of belt 60, except when pressed inwardly as hereinafter described, substantially in alignment with the edge of the channel as defined by the vertical flange of angle 57.

Between the inner and outer flights of each conveyor belt 60 means are provided to normally yieldingly force the greater portion of the length of the inner flight between the rollers 62 into position to overlie the edge of the conveyor belt 52, as shown in full lines in FIG. 7, to cause cans conveyed through the adjacent channel to be closely confined between such inner flight portion and the dividing wall whereby the cans will be rotated by the belt 60 as they are carried through this portion of the channel. Referring particularly to FIGS. 4, 6 and 7 the means for this purpose comprises a plate 68 adapted to be spring pressed, except when withdrawn by means to be described, against the rear side of the inner flight for the greater portion of the length thereof. Plate 68 is carried by brackets 69 which form elements of a pair of spaced pantographs indicated generally at 70 by which the plate 68 is supported from the frame for movement toward and away from the edge of the conveyor belt 52. Each pantograph comprises, in addition to bracket 69, links 71 and 72 each having one end pivotally secured to bracket 69. The other end of link 72 is pivotally mounted on a bracket 73 rigidly connected to the machine frame. The corresponding end of link 71 is fixedly mounted on a shaft 74 as by being keyed thereto the ends of the shaft being pivotally mounted in suitable bearings in bracket 73. The link 71 of one of the pantographs (namely that to the right as viewed in FIG. 4) also includes an angularly extending projection 75 (FIG. 7). One end of an adjustable link 76 is pivotally connected to the outer end of projection 75, the other end of link 76 having a pin 77 fixedly mounted thereon. Pivotally mounted on pin 77 is one end of a link 78, the other end of which is pivotally mounted on a fixed bracket 79 projecting from the machine frame. Another link 80 has an end pivotally mounted on pin 77, the other end of link 80 being pivotally connected to the core member 81 of a conventional pull type solenoid indicated diagrammatically at 82. When the solenoid 82 is de-energized plate 68 is spring pressed into its operative position illustrated in full lines in FIG. 7, and the core of the solenoid is held in its extended or outer position, by a compression spring 89.

As will be apparent, energization of solenoid 82 will cause the core thereof to move to the left as viewed in FIG. 7 which in turn, through the linkage illustrated and pantographs 70, will, against the action of spring 89, move plate 68 from its full line position as illustrated in FIG. 7, in which it holds the belt 60 in position to engage and rotate the cans 36, to its position illustrated in dot-and-dash lines where the belt is out of contact with the walls of the cans carried by the conveyor. It will further be noted that when the solenoid is de-energized and the parts are in the position shown in full lines in FIG. 7, links 76 and 78 are in an over-the-center position thereby assisting spring 89 in resisting outward movement of plate 68 as the cans are engaged and rotated by belt 60, as hereinbefore set forth.

In order that belt 60 will remain taut when plate 68 is moved out of contact with the inner flight thereof means are provided to force the outer flight outwardly upon such movement of the plate. This means comprises

rollers 83 and adapted to engage the inner face of the outer flight at points substantially opposite to the ends of the plate and mounted for rotation in suitable clevises 84. The clevises 84 are secured to and movable with the brackets 69 so that the rollers 83 will be held out of engagement with the outer flight of the belt when the plate 68 is positioned to press the inner flight against the cans and the rollers will engage and force the outer flight outwardly when the plate is moved out of contact with the inner flight of the belt.

Solenoid 82 is to be energized to move plate 68 away from the inner flight of belt 60 and the belt out of contact with a can to stop the rotation thereof when the ears of the can lie in a plane extending transversely of conveyor 15 34. To achieve this result a plate 90 is supported adjacent the end of conveyor 34 to extend longitudinally thereof for approximately the distance between pulleys 62 and at the level of the bail ears of the can carried by the conveyor. Plate 90 (see particularly FIGS. 6 and 8) 20 is supported adjacent the ends thereof by links 91 each pivotally secured to a projection 92 extending rearwardly from plate 90 and to a bracket 93 fixedly mounted on a frame member 94 which in turn is supported from frame member 55 by brackets 95. Plate 90 is urged inwardly 25 toward conveyor 34 by spring tension, e.g. by a spring 96 connected between one of the links 91 and a fixed frame member, the extent of such movement being limited by an adjustable stop 97 carried by an extending end of the right hand bracket 93 and adapted to be contacted by link 91 pivotally connected thereto (FIGS. 4 and 8). When link 91 is against stop 97 plate 90 is so positioned 30 with respect to the edge of conveyor 34 that it is out of contact with the wall of a can 36 but will be contacted and moved outwardly away from the edge of the conveyor by a bail ear 37 or by the portion of the bail 38 protruding therefrom as the can is rotated to bring the bail ears into proximity to a plane transverse of the conveyor.

40 Mounted on frame member 94 is a micro-switch 100 (see FIGS. 4 and 6) having an actuating arm 101 terminating in a roller 102 maintained in contact with plate 90 as by spring means (not shown) incorporated in the switch. Micro-switch 100, which is connected into the circuit of solenoid 82, is in its open position as illustrated in FIG. 4 and the switch is closed to energize the circuit of the solenoid upon outward movement of the plate 90 by the bail ear or bail portion therein as above set forth. In order to prevent a bail, which may be positioned on a can at the level of the plate 90, from engaging and accidentally moving the bar to its solenoid energizing position before the can enters the orienting station and is rotated by the belt 60, a curved finger 103, secured to the left end of the frame member 95 at the level of the bar 90 and in advance of the orienting station, engages a bail so positioned to deflect it either above or below the bar.

60 In the operation of the bail ear orienting means, as a can is conveyed through the channel between dividing wall 40 and continuously running belt 60, with the portion of the inner flight of the latter in its operative or full line position of FIG. 7, the can is rotated until an ear of the can or a portion of the bail projecting therefrom contacts plate 90. Rotation of the can continues with plate 90 being pressed outwardly against the action of spring 96 until the plane of the bail ears is at right angles to the conveyor and the plate is at the limit of its outward movement. As plate 90 substantially reaches this final position actuating arm 101 has been swung clockwise to the point where it closes the contact of micro-switch 100 with the result that solenoid 82 is energized to withdraw plate 68 from contact with inner run of the belt 60 whereupon rotation of the can ceases. Micro-switch 100 is maintained in its closed position, and the solenoid energized, by the continued pressure of the ear or bail portion against the plate for the remainder 65 70 of the travel of the can through the bail orienting station.

As a can leaves the station plate 90 is again moved toward conveyor 34 by spring 96 whereby switch 100 is opened, the solenoid de-energized and plate 68 moved inwardly by spring 89 to position the inner flight of the belt 60 for operation on the next can to be carried through the station.

The effective can turning length of the belt 60 and the speed of movement thereof is correlated to the speed of travel of conveyor 34 to provide for sufficient rotation of a can to bring its ears into the desired transverse position irrespective of the position in which the bail ears may be when the can enters the station. It will be understood that but a single can passes through each channel of the bail ear orienting station at a time, the rate of feed of cans to conveyor 34 being regulated to this end. After leaving the bail ear orienting station the cans continue to move down the channels to the bail flipping station 46 now to be described.

Referring particularly to FIGS. 3, 4, 5, 9, 10 to 10-d and 11 the bail flipping station comprises means located adjacent the outer edges of each channel for flipping the bails. Inasmuch as the mechanism for the two channels are substantially identical or mirror images, only one of these devices, namely the one nearest to the viewer in FIG. 4, will be described in detail. Each bail flipping means comprises a pair of star wheels 110 and 111 mounted for rotation with shafts 112 and 113, respectively, the shafts in turn being supported in suitable bearings 114 carried by frame member 55. Star wheels 110 and 111 are at a level to be contacted by the cans below any position of the bails. Each of the star wheels defines four arcuate recesses in the perimeter thereof the recesses having a radius substantially equal to that of the cans. The star wheels have hubs 115 and 116 respectively provided with diametrically opposed notches 117 with diverging walls and in which dogs 118 are pivotally mounted adjacent the inner ends of the notches for rocking movement therein. Referring particularly to FIGS. 10 to 10-d and specifically to the star wheel illustrated at the left of said figures, which exemplifies both star wheels, said notches are defined in part by an abutment wall 119 to be contacted by the adjacent face of the associated dog when the dog is in its active position as will be hereinafter referred to. The relationship of the abutment walls 119 of the opposed notches is such that when the dogs are in such active positions their remote faces will lie in a common diametric plane. Each dog is urged toward the side of the notch away from its abutment surface by spring means 120 suitably comprising a coil spring received in a recess of the hub, the spring means for one of the dogs being shown in dotted outline in FIG. 10.

A bar 121 is mounted for swinging movement on a pin 122 located equidistant between shafts 112 and 113 and in the vertical plane thereof. Bar 121 includes ends 123 adapted to ride on the peripheries of hubs 115 and 116 in positions to be contacted by dogs 118, the bar being yieldingly maintained with its ends riding on the hubs, except when the bar is positively rotated away therefrom by means hereinafter described, by a tension spring 124 having one end connected to the bar and the other to a fixed frame member of the machine.

Also mounted for pivotal movement on pin 122 but below bar 121 are a pair of plate members 130 (see FIG. 11) projecting in opposite directions from pin 122 and each carrying a brake shoe 131 formed with a facing of any suitable friction composition and positioned, when the plate members 130 are rotated toward conveyor 34, into frictional contact with cans held by the star wheels in a stopped position, such positions to be later described, to prevent rotation of the cans by the action of the bail flipping means. Plate members 130 include ears 132 supporting ball-shaped abutment members 133 adapted to be contacted by the heads 134 of bolts 136 secured in a bar 137. Bar 137 is, in turn, secured to a plate bracket 138 as by screws 139 (see FIG. 5). Plate bracket 138

is pivotally mounted for movement toward and away from conveyor 34 by means hereinafter described. Plate members 130 are caused to rotate on pin 122 upon outward swinging movement of plate bracket 138 by springs 135 having ends connected to pins 140 carried by the plate members and bar 137, respectively.

Plate bracket 138 (FIG. 9) is mounted on a pivot pin 141 the ends of which are received in ears 142 projecting from a bracket 128 secured to frame member 55. A relatively narrow downward extension 143 of the plate bracket has an end thereof pivotally connected as at 144 to a link 145 the other end of which is pivotally connected to the core member 129 of a pull type solenoid 146.

A crossbeam 147 is formed at the upper end of plate bracket 138 at approximately the height of the upper ends of the cans carried by conveyor 34. Mounted in suitable bearings in crossbeam 147 adjacent the ends thereof, and opposite cans held in stopped position by star wheels 110 and 111, are stub shafts 148 projecting toward conveyor 34 their projecting ends having disks 149 and 150 keyed thereto each disk carrying an annular series of flipper members 151 projecting from the face thereof toward the conveyor to overlie the margin of the latter in a tilted position of plate bracket 138 to be hereinafter described. Flipper members 151 comprise semirigid rods of rubber, plastic, or other resilient material.

Disks 149 and 150 are driven in counterclockwise and clockwise directions, respectively, as indicated by the arrows (FIG. 5) whereby flippers 151, when plate bracket 138 is tilted toward conveyor 34, overlie the margins of the conveyor and strike the can bails in any position they may have and cause them to rotate into positions where they lie against the front of the can to the right, and the rear of the can to the left, as viewed in FIG. 5. The disks are continuously driven through the medium of pulleys 152 keyed or otherwise secured to stub shafts 148, idler pulleys 153 mounted for rotation on stub shafts 154 also carried by crossbeam 147, pulleys 155 carried by stub shafts 156 mounted in bearings carried by bracket 138, and belts 157. Shafts 156 are geared together for joint rotation but in opposite directions by gears 158 keyed or otherwise secured thereto. Shaft 156 to the left, as viewed in FIGS. 4 and 5, has a pulley 159 keyed to an inwardly projecting end thereof (FIG. 9), pulley 159 being driven by a belt 160 in turn driven by a pulley 161 keyed to constantly rotating shaft 66 forming part of the drive of the belt 60 at the bail ear orienting station.

A platform 170, on which solenoid 146 is mounted is supported from frame member 55 by bracket portions 171 extending from the platform (FIGS. 5 and 9). Secured to the rear edge of platform 170 is a column 172 extending upwardly and terminating in an upper end at substantially the level of crossbeam 147 (see FIGS. 3 and 9). A tension spring 173 has its ends secured, respectively, to crossbeam 147 and to the upper end of column 172, the spring tending to maintain bracket 138 and the mechanism carried thereby in a vertical position with the lower portion 174 of bracket extension 143 against frame member 55 (see FIG. 9).

A plate 175 is secured to column 172 as by stud 176, plate 175 being notched as at 177 to receive an end portion of a pawl lever 178 pivoted as at 179 to the edge of plate bracket 138. The other end of pawl lever 178 is provided with a pawl hook 180. The construction of the pawl hook and the relative locations of pivot 179, and plate 175 are such that when bracket 138 is in its rest position, the full line position illustrated in FIG. 9, the pawl hook 180 is beneath bar 121. When however plate bracket 138 and its associated mechanism is swung on its pivot 141 in a clockwise direction as viewed in FIG. 9 to the tilted dot-and-dash line position shown in that figure the pawl hook swings in an upward arc into contact with the underside of bar 121 substantially at the forward edge thereof under the influence of a spring 169

connected between the end of lever 128 and the column 172 as shown in FIG. 9, and, as the swinging movement of the plate bracket continues, the pawl hook springs into position to engage the forward edge of bar 121 for the purpose hereinafter set forth. The final clockwise rotated position of bracket 138 is determined by engagement of head portion 181 of the core member 129 with the housing of solenoid 146 (FIG. 9).

Referring now particularly to FIG. 11, shaft 112 of star wheel 110 has a cam 182 keyed thereto for rotation therewith. An actuating lever 183 of a normally closed micro-switch 184, supported from frame member 55, carries a roller 185 adapted to ride on cam 182. Micro-switch 184 is in the circuit of the coil of an adjustable timer 187 of a commercial type, the timer having a normally closed switch 188. The circuit is energized by the closing of the micro-switch to start the timer 187 and energize the circuit of the solenoid 146. Switch 188 remains closed for a set time period and then opens to de-energize the solenoid circuit and remains open until micro-switch 184 has been opened. The circuits of both the timer and the solenoid are connected into main power leads 189.

The operation of the bail flipping mechanism will now be described with reference to FIGS. 10-10-d in which the star wheels are shown in dot-and-dash outline. Starting with the condition of the apparatus in which there are no cans in the bail flipping station and star wheels 110 and 111, and the ends of bar 121 in relation to the dogs 118 in the hubs of the star wheels, are in the positions illustrated in FIG. 10. As the first can 36a is brought by conveyor 34 into contact with, and then conveyed past, star wheel 110 the star wheel is freely rotated by the can to the position illustrated in FIG. 10-a. Star wheel 111 has remained stationary. Can 36a continues to travel with the conveyor into contact with star wheel 111 which is rotated by the movement of the can to the position illustrated in FIG. 10-b at which point a dog 118 in the hub 116 of star wheel 111 is contacted by the end of bar 121 and moved, against the action of its spring 120, into contact with the abutment or shoulder 119, rotation of the star wheel 111 being stopped thereby and the can held stationary against further travel with the conveyor. Thereafter, or in the meantime, a second can 36b is carried by the conveyor into contact with star wheel 110 which is rotated thereby through the position illustrated in FIG. 10-c, in which position the adjacent end of bar 121 contacts the approaching dog 118 in the hub 115 of star wheel 110 to a final locked position in which the dog is brought into contact with the adjacent abutment or shoulder 119. At this point rotation of the star wheel stops and the can 36b is held against further travel with the conveyor. Both cans 36a and 36b are now in position for the bail flipping operation.

The contour of cam 182 on shaft 112 is such that as the star wheel 110 is rotated to the position shown in FIG. 10-c roller 185 of actuating lever 183 of micro-switch 184 is in position to ride off of a high portion of the cam and into one of a pair of diametrically opposed notches 168 formed in the cam, all as illustrated in FIG. 11. As the star wheel 110 completes its rotation to its final locked position roller 185 rides into the notch in the cam permitting the closing of micro-switch 184 and energizing the circuit to the timer 187 and solenoid 146. Upon energization of solenoid 146 plate bracket 138 and the mechanism carried thereby is swung in a clockwise direction as viewed in FIG. 9 from the full line position to the tilted dot-and-dash position indicated in that figure whereby the constantly rotating disks 149 and 150 are swung toward conveyor 34 and flippers 151 brought into the location previously mentioned in which they will contact the bails of cans 36a and 36b and, unless the bails happen by chance to be in such positions, flip the bail of can 36a against the front thereof and the

bail of can 36b against the rear thereof. The timer 187 is preferably set to maintain solenoid 146 energized for a time sufficient to permit several revolutions of the disks 149 and 150 to insure that the bail flipping action is completed.

Upon the above described swinging movement of plate bracket 138 to its tilted position plate members 130 are rotated on pin 122 through contact of abutment members 133 with heads 134 of bolts 136 to bring brake shoes 131 into engagement with cans 36a and 36b and hold them against rotation during the flipping operation.

When the switch 188 opens at the end of the set time period of the timer solenoid 146 is de-energized and bracket 138 swings back again to the vertical position under the tension of spring 173. Simultaneously plates 130 are rotated on pin 122 under the tension of springs 135 to resume the positions illustrated in FIG. 11 with the brake shoes out of contact with the cans.

The rotation of plate bracket 138 toward its vertical position retracts pawl lever 178 to cause pawl hook 180, which was moved to engage the forward edge of the bar 121 during movement of the plate bracket to its bail flipping position, to rotate the bar 121 in a clockwise direction, as viewed in FIG. 10-d, sufficiently to remove the ends 123 from behind the dogs 118 with which the ends had been engaged. Immediately upon their release these dogs swing, under the influence of their springs 120, into engagement with the notch walls opposite the abutment surfaces. As the retraction of the pawl lever 178 continues the pawl hook swings through a downward and rearward arc of movement to slip from behind bar 121 thereby releasing the bar for rotation in a counter-clockwise direction under the influence of its spring 124. Due, however, to the rotation of the dogs upon release, 30 as previously mentioned, they now underlie the ends 123 of bar 121. This position of the parts is illustrated in full line in FIG. 10-d. The star wheels having been released from their locked positions the cans now resume their travel with conveyor 34, both star wheels being 40 rotated by the movement of the cans, this condition of the parts being illustrated in dotted lines in FIG. 10-d. Movement of the star wheel 110 also moves the high portion of the cam 182 beneath the roller 185 to again open switch 184. As will be noted star wheel 110 and 45 cam 182 are now in position for the start of a new cycle of operation and star wheel 111 is rotated to its starting position, indicated in FIG. 10, by can 36b as this can is moved out of the bail flipping station. As additional cans are carried through the channel the operations above 50 described are repeated.

Cans 36 with their bail ears lying in planes transverse of the conveyor 34 and with their bails now alternately lying on the forward and rearward sides of the cans continue to travel with the conveyor to the case loading station 47. Conveyor 34 terminates adjacent the loading station 47 and deposits the cans on a transfer plate 186 from whence they are pushed into the loading station by following cans. The mechanism and operation of the latter station will be described in detail but to aid in the 55 understanding thereof a relatively brief description will first be given of the critical parts thereof and their sequence of operation.

Referring particularly to FIGS. 1, 12, 13 and 14 the can loading station comprises a can assembly and orienting platform illustrated generally at 190 positioned to receive the cans as they are shoved in two lines across the transfer plate by following cans in the two lanes of conveyor 34. The platform is adapted to receive a case load of cans, i.e. four cans in the example illustrated, one pair from each line. As will be understood each pair so received was also in paired relationship at the bail flipping station so the leading can of each pair has its bail lying against its forward side and the trailing can has 60 its bail resting against its rear side.

11

The forward movement of the cans onto the platform continues until the leading cans in each pair contact a rail 293 secured to the platform at the forward edge thereof. The cans travel forwardly between a head 250 of the plunger mechanism 48, a downwardly retractable gate 252 (see FIG. 14), and an upwardly retractable divider member 239 (FIG. 19) adapted to be inserted between the two pairs of cans, both the gate and the divider member being in their operative positions at this time. When the leading cans are in contact with rail 293 the cans of one pair are approximately centered on the faces of a pair of rotatable gears 197 and the cans of the other pair are approximately centered on the faces of a pair of gears 198, the gears forming a portion of the floor of the platform and being approximately the diameters of the cans.

Inasmuch as the cans are advanced onto the platform solely by the shoving action of the following cans means are provided to segregate the two pairs assembled on the platform from the following cans before the case loading operation takes place. This means comprises a gate 220 (FIGS. 14 and 19) adjacent the forward end of plate 186 the gate being adapted to be moved upwardly into position to bar further movement of the following cans across the transfer plate when the assembled group is given a further forward movement hereinafter described. Gate 220 comprises a row of pins 224 individually retractable against spring tension when the gate is moved upwardly into operative position.

The means for segregating the assembled cans also includes means for giving the assembled cans the further forward movement mentioned above, comprising a mounting for the platform 190 and an actuating means therefor by which the platform is shifted from a position adjacent transfer plate 186, the full line position of FIGS. 13 and 14, in which position only a narrow space remains between the plate and platform through which the pins of gate 220 project when the gate is in its can restraining position, to a remote position indicated in dotted lines in FIG. 14. As will be noted from the showing of FIG. 14 the forward portion of the following cans will overlie some of the pins of gate 220 and these pins will be depressed as the gate rises. Other pins will however confine the following cans against further forward movement when the platform is shifted to its remote position, the assembled cans being thus segregated from the following cans.

During the shifting movement of platform 190 gears 197 and 198 are rotated in the directions indicated by the arrows (FIG. 14) to rotate the cans supported thereby to position the vertical planes of the bail ears thereof diagonally of the corners of the assembled group. During or upon the shifting of the platform, gate 252 is lowered to bring the upper edge level with or below the platform floor and divider member 239 is raised from its position between the pairs of cans and thereafter upon completion of the movement of the platform to the dotted line position of FIG. 14, the plunger mechanism is operated to cause plunger head 250 to first push the pair of cans adjacent thereto in a direction at right angles to the original line of movement into contact with the other pair of cans and then push the four cans in grouped formation off platform 190, across a table 210 and into a carton 50 previously opened at the case opening station and now positioned with its open ends in alignment with table 210.

Table 210 is provided with rails 280 extending a portion of the table length to confine the cans against lateral movement during the initial part of their travel across the table. A pair of pivoted rail members 281 when in one position, the dotted line position of FIG. 14, form slightly diverging continuations of rails 280, the rail members terminating at a point between end flaps 282 of the carton. Rail members 281 serve the further function of swinging flaps 282 from a somewhat converging position they may tend to assume after the carton opening action, to a fully open position and maintaining them in that position dur-

5 10 15 20 25 30 35 40 45 50 55 60 65 70 75

12

ing the movement of the cans into the carton. Thus rail members 281 during the greater part of the loading cycle are in the full line position as illustrated in FIG. 14, in order to permit the positioning of carton 50 in alignment with table 210. However in advance of the movement of the cans across the table the rail members are swung to their dotted line position to perform the functions noted above. It should be mentioned that the top and bottom flaps of the carton do not interfere with the loading operation as these flaps are maintained above and below the open end of the carton by elements of the mechanism (not shown) as is conventional.

During the movement of the assembled cans into a relatively tightly fitting carton there is a tendency for the cans to be rotated through frictional contact of the bail loops and/or the can walls with the carton walls. Means are provided to prevent such rotation comprising in part pads 285 of deformable material such as rubber on the head 250 of the plunger mechanism and a holding device 286 comprising a rod 287 on which is pivotally mounted a bracket 288 having pins 289 extending at angles from the bracket at both ends thereof and supporting a series of disks 290 of deformable material, such as rubber, between the heads of the pins and the bracket 288. Holding device 286 is adapted to be moved through the open rear end of the carton 50 into the position illustrated in FIG. 14 under spring tension. As the group of cans is pushed into the carton the leading cans contact the head of holding device 286 just before the walls or bails of the cans contact the carton walls, the head thereafter moving with the group of cans during the remainder of their travel into the carton whereby any tendency of the cans to rotate is opposed by the frictional resistance of the pads 285 and device 286.

The sequence of the several operations performed at the loading station and described above is controlled by a main cam shaft 206 which makes one revolution for each loading sequence and thereafter remains stationary until another carton load of cans is assembled on platform 190. Rotation of the cam shaft is initiated by a control system indicated generally at 291 including feelers 292 in position to be contacted by the leading cans as they are shoved onto the platform, the feelers activating the control system when, and only when, both leading cans are fully advanced to their proper positions on the platform as will be hereinafter explained.

The construction of the several mechanisms at the loading station and the means by which the required operations are obtained will now be described in greater detail.

Referring particularly to FIGS. 12 to 27 inclusive and first to FIGS. 12, 13 and 14 platform 190 comprises a housing structure 191 mounted for sliding movement in a longitudinal direction, with respect to conveyor 34, on rods 192 having their ends supported in bearings 193 carried by end plates 194 which are in turn fixed to frame members 195. The upper surface of housing 191 together with the faces of gears 197 and 198 constitutes the floor of the platform 190 which is at the level of transfer plate 186.

Gears 197, constituting a pair, are supported in intermeshing relationship by and are affixed to vertically extending shafts 199. Similarly gears 198 constituting a pair, are supported in intermeshing relationship by and affixed to vertically extending shafts 200, the several shafts being supported for rotation in suitable bearings 201 carried by a partition plate 202 of housing 191, the hubs of the gears also resting on the partition plate. Shafts 199 and 200 of the rear gears of each pair, the gears to the left as viewed in FIG. 13, are extended through their bearings 201 the extending ends carrying pinions 216. Pinions 216 mesh with rack teeth 203 formed on the outer edges of short angle bars 204 one of the bars being secured in fixed position on each rod 192 (FIG. 22). Housing 191 is shifted on rods 192 from the position as illustrated in FIG. 13, in which the rearward edge of the

platform is relatively closely adjacent transfer plate 186, to its forward or remote position illustrated in FIG. 14 by dam means. Said means comprises a cam 205 carried by the main cam shaft 206 the cam having a peripheral groove defining a cam track 207 receiving a follower roller 208 mounted for rotation on a follower lever 209. The follower lever is pivoted for rocking movement on a shaft 217 supported on frame members 211 (FIGS. 12 and 13). The upper end of follower lever 209 is forked as at 212 to slidably receive a block 213 rotatably mounted on a pin 214 which in turn is carried in ears 215 projecting downwardly from the bottom of housing 191.

The housing 191 is shifted under the influence of cam 205 at certain times to move the platform, as explained above, from its can receiving to its remote position in which the platform and the cans thereon are brought into alignment with table 210 (FIG. 14). As the housing is shifted gears 206 meshing with their respective rack teeth 203 are caused to rotate to in turn rotate a gear of each pair, the gears to the left as viewed in FIG. 13, said gears in turn rotating their companion gears through the intermeshing engagement therewith. The pitch of the rack and gear teeth are correlated to the length of the stroke to secure approximately 45 degree arcs of rotation of the gears whereby the cans are rotated to position the vertical planes of their bail ears diagonally across the corners of the group of cans as previously mentioned.

Gate 220 (FIG. 19) which prevents further forward movement of the following cans as the platform is shifted to its remote position comprises the row of pins 224 the pins being slidably mounted in aligned perforations in a pair of spaced rails 222 interconnected by end members 223. Each pin 224 has a collar 225 affixed thereto below the upper rail 222 and carries a compression spring 221 surrounding the pin between collar 225 and lower rail 222. Bearings 226 extending outwardly from end members 223 have openings or holes therein to slidably receive vertical rods 227, a rod being located adjacent each end of the gate 220. Each rod 227 is supported for sliding movement in spaced bearings 228 carried by upper and lower machine frame members 229. Gate 220 is adapted for movement with and for movement relative to the rods 227 and for this purpose bearings 226 are confined between collars 230, fixed in position on the rods as by set screws or the like, and compression springs 232 surrounding the rods between the bearings and collars 233 also in fixed positions on the rods.

Rods 227 at their lower ends are connected by a cross-bar 234 having fixed thereto a follower 235 on which is rotatably mounted a follower roller 236 adapted to ride in the cam track 237 formed in one side face of a cam disc 238 keyed or otherwise secured to the main cam shaft 206 for rotation therewith. Rods 227 extend upwardly from the upper bearings 228 the upwardly extending rods carrying the supporting means for divider member 239. The supporting means comprises a block 240 mounted on a square bar 241 received within a groove in the block. The block is secured to the bar by a pin 242 projecting from the block through a hole in the bar and having a nut 243 threaded thereon. The ends of bar 241 are secured in sleeves 244 mounted for vertical adjustment on rods 227 and adapted to be fixed in any adjusted position by suitable means such as that indicated at 245.

Movement transmitted to the rods 227 by the cam track 237 in turn moves divider 239 between its lowered operative position between the cans at a level slightly above the bail ears, as illustrated in FIG. 19, and a raised inoperative position in which it clears the tops of the cans, cam track 237 having high and low portions designed to control the extent of such movement. However gate member 220 requires a movement of lesser extent and for this purpose stops 246 are provided on upper frame members 229 for contact with abutment plates 247 projecting outwardly from the bearings 226 of the gate 220. When

the abutment plates are brought into contact with stops 246, as the follower 236 approaches the high point of the cam track, further upward movement of bearings 226 and hence of gate member 220 is prevented by contact of stops 246 with plates 247, springs 232 being compressed upon continued upward movement of the rods.

At the end of a carton loading operation cam shaft 206 is stopped with follower 236 in the low point of the cam track and with the parts controlled by the cam in the positions illustrated in FIG. 19. The next group of cans then is pushed onto the platform 190 and upon completion of their movement the control system 291 initiates rotation of the cam shaft in the direction indicated by the arrow (FIG. 19) gate 220 immediately being raised sufficiently to cause the pins thereof, which are not blocked off by overlying following cans, to perform their can holding function. Continued travel of the follower toward the high point of the cam track raises the gate until abutments 247 contact stops 246, divider 239 however continuing to be raised by the rods until the follower is in the high point of the cam track at which time the divider is above the tops of the cans. The cam track is designed to maintain divider 239 in its raised position during the removal of the cans from the platform by plunger mechanism 248 and thereafter to gradually lower it to its operative position, and to maintain the gate in position to prevent forward movement of the following cans until the plunger means has completed its case loading operation and returned to its rest position and the cycle of operation, as measured by one revolution of the cam shaft, is substantially completed.

Referring particularly to FIGS. 20 to 22 gate 252, which as previously explained defines, in effect, a side wall of the platform while the cans are being shoved thereon, comprises a plate member 253 secured to a bar 254 for vertical reciprocating movement therewith. Bar 254 is mounted for sliding movement in a way (FIG. 21) defined by members 255 carried by and secured to a plate 256 supported by brackets 257 from housing 191, whereby the gate also partakes of the longitudinal shifting movement of the housing and platform. Vertical movement of bar 254, and hence of the gate 252, is controlled by cam 258 keyed to the main cam shaft 206 for rotation therewith. A cam follower lever 259, having a follower roller 260 received in a cam track 261 formed in one side face of cam 258, is pivoted on a shaft 262 supported on the frame members 211 (FIGS. 13, 20 and 22). The end of the lever opposite follower 260 is connected to bar 254 by a link 263 having an eye at one end relatively loosely receiving a pin 264 projecting from a block 265 projecting from bar 254, and an eye at the other end relatively loosely receiving a pin 266, projecting from lever 259, the arrangement providing for the longitudinal shifting movement of the bar with the housing 191. The cam track 261 is designed to maintain gate 252 in its raised operative position during the movement of the cans onto the platform and thereafter immediately lower the gate to bring its upper edge into the plane of or below platform 190 and maintain it in such position until the loading cycle is substantially completed at which time the gate is again raised to the position of FIG. 22.

Referring now to FIGS. 14, 17 and 18 rail members 281, which in one position define continuations of rails 280 of table 210 and serve to open and hold open the end flaps of the carton, are supported for swinging movement on vertically extending shafts 300 and 301. The projecting end portion of shaft 300 is received in and affixed to a rearwardly projecting ear 302 of one of the rail members 281. Shaft 300 extends downwardly below the table top and is supported in bearings in the legs of a bracket 304, U-shaped in cross section, which is carried by the supporting framework of the table. Secured to shaft 300 is a bevel gear 305 in intermeshing engagement with a bevel gear 306 secured to the end of a shaft 307 extending transversely beneath table 210 and mounted for rotation

tion in a bearing 308 in the base of bracket 304 and in a bearing 303 carried by a bracket 309 secured to the machine frame adjacent the opposite side of the table.

The other rail member 281 is, in a similar way, mounted for rotation with shaft 301 carried in suitable bearings in the legs of a bracket 311 supported in this instance from a plate 312 mounted in fixed position substantially at the height of the top of table 210. A bevel gear 310 fixed to the shaft 301 is in meshing engagement with a bevel gear 313 fixed to a horizontal shaft 314 mounted for rotation in bearings in the base of the bracket 311 and in a housing portion 315 of plate 312. Shaft 314 is driven from shaft 307 through sprockets 316 and 317 keyed to the shafts 314 and 307, respectively, and a sprocket chain 318.

Shaft 307 is rotated or rocked by a cam 320 keyed to the main cam shaft 206. The cam has a cam track 321 receiving a follower roller 322 mounted on one end of a follower lever 323 centrally pivoted on the shaft 262. The other end of lever 323 is pivotally connected to one end of a link 325, the other end of which is pivotally connected to one arm of a bellcrank 326 mounted for rocking movement as at 327 on the machine frame. A second arm of bellcrank 326 is pivotally connected to one end of a link 328 the other end of which is pivotally connected to a lever arm 329 mounted in fixed position on shaft 307.

Cam track 321 is designed to, through the various mechanisms described above, rock shaft 307 through arcs and at times to in turn rotate shafts 300 and 301 to swing the rail members 281 between the full and dotted line positions shown in FIG. 14 to perform the functions heretofore ascribed to the rail members.

Plunger mechanism 48 will now be described, reference being made particularly to FIGS. 13 to 16, inclusive. The head 250 of the plunger mechanism comprises a lower grooved head piece 335 (FIG. 13), the head piece receiving and supporting a pad 285 of deformable material, as previously referred to, in an adjusted position longitudinally of the groove thereof whereby the pad is adapted to contact the lower portions of the cans on gears 197. The head 250 includes a second head piece 337, also carrying a pad 285, to contact the cans adjacent their upper ends. Head piece 337 also supports plate member 339 defining a downwardly diverging pair of wings 340 shaped to clear the bail ears and bails as the cans are moved onto gears 197 the platform shifted and the gears rotated. The wings resist any tendency of the bails of the cans, which are the trailing pair during the case loading operation, to swing toward horizontal positions upon contact with the walls of the case as the cans are shoved therein. Head 250 is supported on a reciprocable structure comprising a right angle bracket 341 one leg of which is secured to the head and a plate 342 extending diagonally of the bracket and having one end also secured to the head (FIG. 16). The other end of plate 342 and an end of the other leg of bracket 341 are fastened to and carried by a supporting plate 345 of a crosshead indicated generally at 346. As will be noted the construction is such that the crosshead and the supporting and driving mechanism therefor now to be described, are offset from the platform 190 and extend in part along the forward side thereof (FIG. 13).

Crosshead 346 comprises spaced sleeves 347 to which plate member 345 is secured, mounted for sliding movement on a rod 348 and a bracket portion 349 connecting the sleeves 347 beneath rod 348. Fastened to bracket 349 on opposite sides thereof are angle members 350 carrying vertically extending pins 351 supporting rollers 352 for rotation thereon. Rollers 352 are adapted to contact opposite sides of a vertical guide flange 353 on a T-bar 354 extending parallel to rod 348 and secured at its ends in a fixed position on the machine frame to prevent turning movement of the crosshead on the bar 348.

The crosshead is driven through reciprocating strokes of a length to move assembled cans from their position on the platform 190, along table 210 and into the carton. The driving means comprises a cam 355 keyed to the main cam shaft 206 for rotation therewith, a pitman 356 pivoted on a shaft 357 and carrying a follower roller 358 riding in a cam track 359 of cam 355 and a linkage and lever system now to be described. The latter comprises an adjustable link 360 pivotally connected at one end to the free end of pitman 356 and at the other end to an intermediate point on a lever 361 having one end secured to a shaft 362. The shaft is carried by spaced bearings, one of said bearings being illustrated at 363 in FIG. 16, mounted in fixed position on the machine frame. The free end of lever 361 is pivotally connected to a bar 364 intermediate the ends thereof. One end of bar 364 is pivotally connected to the free end of a lever 365 the other end of which is secured to a shaft 366 mounted for rocking movement in suitable bearings 367 on the machine frame. The other end of bar 364 is pivotally connected to an adjustable link 368 the other end of which is pivotally connected to crosshead 346 as at 369.

Cam track 359 is designed to, upon rotation of main cam shaft 206 and after the cans have been assembled on 25 the platform and the platform shifted to its advanced position by cam 205, and gate 252 lowered by cam 258, activate the plunger means through the mechanism described above to advance the cans across table 210 and into the carton and then return the plunger head to its 30 rest position.

Holding device 286 which cooperates with the plunger head 250 in resisting rotation of the cans as they are pushed into the carton, will now be described in more detail. Rod 287, which supports disks 290 and the other 35 elements of the head of the device, has a substantially horizontal portion 380 of a length to project from the rear of the carton, when the device is in its full line position illustrated in FIG. 12, the rod thereafter continuing through a substantially U-shaped bend to avoid contact with elements of the case supporting means and terminating in a 40 downwardly extending leg 381 pivotally mounted as at 382 on the machine frame. The rocking movement of rod 287 on its pivot 382 to move the head between the full line and dotted line positions of FIG. 12 is in part controlled by a cam 383 keyed to a stub shaft 384 mounted 45 in suitable bearings (not shown) on the machine frame. A follower lever 385 is pivoted as at 386 to a fixed bracket 387, follower lever carrying a follower roller 388 in position to ride on the periphery of cam 383. The free end 50 of follower lever 385 is pivotally connected to an adjustable link 389, the other end of the link being pivotally connected at 390 to leg 381. Shaft 384 is driven from the main cam shaft 206 by sprocket wheels (not shown) keyed to cam shaft 206 and to shaft 384, respectively, and a 55 sprocket chain 391. The two sprockets are of the same diameter whereby shaft 384 will be rotated to the same extent as cam shaft 206.

Follower 388 is urged toward the periphery of cam 383 and the holding device is moved from the dotted to the 60 full line position of FIG. 12 by a tension spring 392 having one end connected to leg 381 and the other end to the machine frame. The profile of cam 383 is so designed that as the leading cans of a group being loaded contact the head of holding device 286, follower 388 is 65 riding on a low portion thereof (FIG. 12). As the cans continue to move into the carton they push the holding device ahead of them against the tension of spring 392 lifting follower 388 from the cam. However as the plunger mechanism reaches the end of its stroke and as 70 the cans reach their final position in the case continued rotation of the cam 383 again brings its periphery into contact with follower 388 which follows it to the high portion thereof to withdraw the holding device to its dotted line position of FIG. 12. Thereafter the follower rides 75 on the high dwell portion to maintain the holding device

in its withdrawn position until the filled carton is moved from its loading position and an empty carton substituted therefor.

Referring now to FIGS. 13 and 23 to 27 inclusive the control system 291 and the drive mechanism for main cam shaft 206, controlled by said system, will be described. The control system includes feelers 292, previously mentioned, each comprising a rod 400 having an end threaded into or otherwise fixedly connected to a hub 401 rotatably mounted on a shaft 402 and adjustably positioned axially of the shaft by a pair of collars 399. Shaft 402 is supported at its ends in brackets 403 projecting from a platform 398 mounted for horizontal and vertical adjustment on rods 397 carried by the machine frame. The rod 400 of each feeler has an integral right angularly extending horizontal portion 405. A plate 406 of substantially trapezoidal shape is welded or otherwise secured to the lower sides of the extending portion 405 and shank portions of each rod 400. The several feelers are spaced on shaft 402 by collars 399 (FIG. 23) so that a pair thereof are in a position to overlie each of the leading cans of the group shoved onto platform 190.

Threaded or otherwise secured in the hub 401 of each feeler and projecting therefrom at an acute angle with respect to rod 400 is a link 407 the outer end of which has an eye receiving the ball shaped head of a pin 408 projecting from one end or the other of a crossbar 409 or 410 (see FIGS. 23 and 24). Crossbars 409 and 410 are in turn centrally pivotally mounted on links 411 and 412, respectively. The ends of links 411 and 412 remote from crossbars are pivotally mounted adjacent the ends of an elongated crossbar 413 centrally pivotally mounted on a slider 414. Slider 414 is mounted for vertical sliding movement in a bearing 415 formed in a plate bracket 416 which in turn is secured to platform 398. The upper end of slider 414 underlies a roller 417 rotatably mounted adjacent the end of the actuating lever 418 of a micro-switch 419 carried on the platform 398. Micro-switch is adapted when closed, the counterclockwise position of the actuating lever illustrated in FIG. 24, to energize a solenoid 420 (FIG. 27) the latter effecting the operation of a clutch controlling the rotation of the cam shaft as hereinafter described.

In the operation of the control system, as cans are shoved forwardly onto platform 190 by a succession of following cans, and first assuming that there are four cans so advanced to provide a full case load, each leading can contacts a pair of the feelers 292 swinging them upwardly and as the cans reach their final positions against rail 293 all four of the feelers will have been elevated to the same level. Swinging of the feelers has caused similar rotation or rocking movements of links 407 with the result that crossbars 409 and 410 are in the raised positions illustrated in full lines in FIG. 24 and in a common horizontal plane. The lifting of the crossbars to a higher but common horizontal plane has in turn lifted bar 413 to the raised horizontal position of FIG. 24, slider 414 rising with bar 413 to rotate lever 418 to close the contact of micro-switch 419 and thereby energize solenoid 420. However if because of the lack of sufficient cans in one of the lanes to push a leading can from such lane to its final position against rail 293, or for some other reason the leading can is not finally so positioned, the pair of feelers intended to overlie such can will not be raised, or completely raised, and bar 413 will be swung on its pivot as a can from the other lane shoves to its final position. As a result slider 414 will not be raised sufficiently to close switch 419. Inasmuch as the leading cans are moved to their final positions only by a succession of following cans the control mechanism described insures that micro-switch 419 will not be closed and the mechanism at the loading station operated unless and until all four cans of a can load are in their allotted position on platform 190.

The use of pairs of feelers, the pivotal mounting of crossbars 409 and 410 on their links 411 and 412, respec-

tively, and the pivotal mounting of the links on bar 413 also adapt the control means for operation of the loading station on small cans to be moved onto the platform 190 in, for example, four lanes rather than two. In such case, and with proper horizontal and vertical adjustment of platform 398 on rods 397, each crossbar will serve two lanes of the smaller cans with one feeler for each lane. In the event a can from one of such two lanes is not properly positioned to underlie its feeler the crossbar operatively connected to such feeler will tilt, rather than be vertically raised, with the result that the corresponding end of bar 413 will also not be raised or slider 414 lifted sufficiently to close micro-switch 419. It will be appreciated that the smaller cans referred to are ordinarily without bails and that in any event the features of the machine relating to the positioning of the bails and bail ears would operate idly or their operation would be discontinued when the machine is used for more than two lanes of cans.

Solenoid 420, which is of the push type with a spring return, is mounted on a bracket 421 supported from the base of the machine. The core 422 of the solenoid is pivotally connected by a link 423 to a lever 424. Lever 424 includes a hub portion pinned or otherwise secured to a stub shaft 425 mounted for rotation in bearings on frame member 426. A follower lever 427 is also pinned or otherwise secured to shaft 425, the follower lever 425 carrying a follower roller 428 adapted to, at certain times, ride on the periphery of a cam 429 keyed to main cam shaft 206.

Lever 424 is adapted when the solenoid is de-energized to be swung in a counterclockwise direction, as viewed in FIG. 27, to bring its free end into the path of an actuating dog 430 of a clutch indicated generally at 431. Clutch 431 may be of any suitable or conventional type to be engaged and released upon movement of dog 430, or a similar actuating member, between two positions. However in the construction illustrated the clutch 431 comprises (FIGS. 26 and 27) a constantly rotating shaft 432 having a hub 433 secured to an end thereof for rotation therewith. Hub 433 encloses a ring 434 having a series of grooves defining internal ratchet teeth. The clutch also includes a driven shaft 435 having a clutch body 436 secured thereto. The outer face of the clutch body is provided with a substantially triangularly shaped depression or notch 437 of a depth to receive an arm 441 of dog 430 in the notch communicating at its inner end with an axially extending cylindrical bore 438. A semicylindrical groove 439 in a hub portion 440 of reduced diameter is in line with the bore.

Dog 430 comprises arm 441, received within notch 437 as aforesaid, from which a pin 442 projects. Pin 442 includes a cylindrical section lying within bore 438 and a substantially semicylindrical shank 443 lying within groove 439. The upper face of semicylindrical shank 443 defines a curved plane of the same radial dimension as the groove 439 in hub portion 440 whereby, when the dog is rotated to the dotted line position illustrated in FIG. 27, hub 433 and ring 434 may rotate relatively to clutch body 436. However upon force being applied to arm 441 tending to rotate dog 430 toward its full line position (FIG. 27), and as soon as an edge portion of shank 443 overlies one of the grooves of ring 434, the dog will rotate whereby a corner of the shank will, upon continued rotation of hub 433, abut against a wall of said groove and engage the clutch. Dog 430 is normally urged toward the clutch engaging position, the full line position of FIG. 27, by a compression spring 445 seated in a recess in the clutch body opposite arm 441.

Shaft 432 is driven from a shaft 448 by sprockets 446 and 447, keyed to shafts 432 and 448, respectively, and sprocket chain 449 (FIG. 25). Shaft 448 in turn is driven by an electric motor or other prime mover (not shown) by a chain drive indicated generally at 450 through a

19

manually operated clutch 451 of a standard type. Shaft 435 has a gear 454 keyed thereto meshing with a gear 456 keyed to the main cam shaft 206. As will be understood while the mountings of the various shafts referred to have not been described they constitute suitable bearings on frame members of the machine as shown particularly in FIG. 25.

In the rest position of the mechanism at the loading station, with cam shaft 206 stationary and solenoid 420 de-energized, follower roller 428 is in engagement with a low portion of cam 429, the free end of lever 424 is behind arm 441 of dog 430 holding the arm against the right hand wall of the notch 437 with spring 445 compressed, all as illustrated diagrammatically in dotted lines in FIG. 27, and clutch 431 is hence disengaged. Upon energization of solenoid 420 by the closing of micro-switch 419, due to the presence of a full load of cans on platform 190, the solenoid core is pushed downwardly against the tension of the solenoid spring to disengage lever 424 from behind the dog arm 441, the dog immediately swinging to its clutch engaging position under tension of spring 445. Upon engagement of the clutch, shaft 435 is rotated with shaft 432 and through intermeshing gears 454 and 456 cam shaft 206 is rotated but at a much lower r.p.m. to, through the various cams previously described, drive sequentially the several mechanisms performing the operations at the loading station. As the cans are removed from the platform 190 by the plunger mechanism, the feelers 292 swing clockwise as viewed in FIG. 13 to open switch 419 and de-energize solenoid 420. Lever 424 is however maintained in the full line position of FIG. 27 with its end clear of arm 441 by follower roller 428 which at this stage is riding on the high circular portion of cam 429. As the cam shaft continues its rotation toward its original or rest position, after the several loading mechanisms have performed their functions, follower roller 428 follows the contour of the cam toward the low point thereof allowing the lever 424 to swing in a counterclockwise direction to its dotted line position of FIG. 27 under the tension of the solenoid spring to position the end of the lever in the path of arm 441. Upon contact of arm 441 with the end of lever 424 dog 430 is rotated to disengage the clutch 431 and the cam shaft comes to rest with the follower 428 in engagement with the low portion of the cam 429.

As will be recognized from the foregoing description of the construction and operation of the several stations the cans themselves serve as the means for instituting each operation. In other words unless a can, or a predetermined number of cans as the case may be, is moved into each station, either by conveyor 34 or by the pushing action of the following cans, such station remains inoperative. It will also be recognized that while the apparatus is primarily adapted for the encasing of bailed cans with two lanes of the cans moving through the several stations and four cans assembled at the loading station, it may, as previously mentioned, be employed for encasing other sizes and types of cans the various features such as the can orienting rotating station, the bail flipping station and the platform gears for imparting a final partial rotation to the cans performing no useful function in such case but, on the other hand, not interfering with the utility of the device as a case loading means. To accommodate various size cans certain of the parts have been described as being adjustably mounted and similarly other parts may be so constructed.

Having thus described the invention in rather full detail it will be understood that these details need not be strictly adhered to and that various changes and modifications may be made all falling within the scope of the invention as defined by the subjoined claims.

What is claimed is:

1. In a machine for arranging cans, having bails secured in oppositely projecting bail ears, for loading into cases, means conveying a succession of said cans, means

20

for grouping a case load of said cans, means for segregating said group from said succession, and means for arranging the cans of said group with their bails and bail ears in predetermined positions including means for positioning the bails of said cans against predetermined sides thereof while the cans are conveyed in said succession of cans.

2. In a machine for arranging cans, having bails secured in oppositely projecting ears, for loading into cases, means conveying a succession of said cans, means for defining two lanes of travel of said cans on said conveying means, means for grouping a case load of said cans, means for segregating said group from said succession, and means for arranging the cans of said group with their bails and bail ears in predetermined positions, said last named means including means adjacent each of the lanes for operation on the cans conveyed therealong and comprising means for orienting the cans with their bail ears transverse to the direction of travel in said lanes, means for positioning the bails of pairs of cans in each lane with the bail of the leading can of a pair against the forward side thereof and the bail of a trailing can of a pair against the rearward side thereof.
3. In a machine as defined in claim 2 wherein said group comprises said pair of cans from each lane and said means for arranging the cans additionally comprises means for rotating the cans in the group to position the bail ears thereof in vertical planes extending across the corners of the group.
4. In a machine as defined in claim 3 wherein said means for segregating said group comprises barrier means interposable between said succession of cans and said group of cans and means for shifting said group of cans away from said barrier means.
5. In a machine as defined in claim 3 wherein there is means to maintain the arrangement of the cans of the group during insertion of said group into a case.
6. In a machine for arranging cans, having bails secured in oppositely projecting bail ears, for loading into cases, means for conveying successions of said cans in two lanes with the vertical planes of the bail ears thereof lying substantially transversely of said conveying means and with pairs of cans in each lane having the bails of the leading cans of the pairs lying against the forward sides and the bails of the trailing cans lying against the rearward sides thereof, means for segregating a group of said cans comprising a pair from each lane, and means for partially rotating the cans of said group to position the vertical planes of the bail ears thereof across the corners of said group, and wherein said segregating means includes a platform onto which said group of cans is pushed by following cans, means for shifting said platform forward, an openable and closable gate means and means to close said gate means to restrain said following cans upon shifting movement of said platform.
7. In a machine as defined in claim 6 wherein said means for rotating said cans of said group comprises gears having faces forming a portion of said platform, each gear face receiving a can of said group, and there is means for rotating said gears.
8. In a machine as defined in claim 7 wherein said means for rotating said gears is operated by said shifting movement of said platform.
9. In a machine for arranging cans, having bails secured in oppositely projecting bail ears, for loading into cases, means for conveying successions of said cans in two lanes with the vertical planes of the bail ears thereof lying substantially transversely of said conveying means and with pairs of cans in each lane having the bails of the leading cans of the pairs lying against the forward sides and the bails of the trailing cans lying against the rearward sides thereof, means for segregating a group of said cans comprising a pair from each lane and means for partially rotating the cans of said group to position the vertical planes of the bail ears thereof across the corners of said

group, and wherein said segregating means comprises a platform onto which said group of cans is pushed by following cans, and means for shifting said platforms forwardly, and there is a table in lateral alignment with said group of cans when said platform is shifted forwardly, there is an openable and closable gate means positioned when closed to isolate said platform from said table, there is means for holding an open-sided case in alignment with said table, and there is means for loading said group into a case comprising plunger means and means for moving said plunger means in forward strokes to move said group of cans off said platform across said table and into said case, and there is means to close said gate means during the movement of said cans onto said platform and to open it prior to the operation of said plunger means.

10. In a machine for loading cans, having bails secured in oppositely projecting bail ears, into cases, means for conveying successions of said cans in two lanes with the vertical planes of the bail ears thereof lying substantially transversely of said conveying means and with pairs of cans in each lane having the bails of the leading cans of the pairs lying against the forward sides and the bails of the trailing cans lying against the rearward sides thereof, means for segregating a group of said cans comprising a pair from each lane, means for partially rotating the cans of said group to position the vertical planes of the bail ears thereof across the corners of the group, and means for loading said group into a container comprising plunger means including a plunger head adapted to contact cans of said group and wherein said plunger head comprises means for restraining upward movement of the bails of the cans contacted thereby.

11. In a machine for loading articles into containers, means for conveying successions of said articles in a plurality of lanes, means for segregating a forward group constituting a container load of said articles from following articles of said succession, the segregating means comprising a platform onto which the articles of said group are shoved by the following articles, means to shift said platform forwardly, gate means mounted for movement between open and closed positions, said gate means in its closed position blocking off following articles from said platform, means for moving said gate means to its closed position prior to the shifting movement of said platform, means for loading said segregated group into a container, and means operated by the receipt of a container

load of articles on said platform for initiating the shifting movement of said platform and the closing of said gate and for thereafter initiating the operation of said loading means.

5 12. In a machine as defined in claim 11 wherein said machine additionally comprises a table adjacent said platform in the shifted position of the latter, a second openable and closeable gate between said platform and said table, means for opening and closing said second gate, fixed side rails on said table extending a portion of the length thereof, swingable side rails for said table, means for swinging said swingable side rails between positions in which they form extensions of said fixed side rails and in which they lie substantially laterally of the table, and means for loading said segregated group into said container comprising a plunger head and wherein said initiating means additionally includes means for initiating movement of said second mentioned movable gate to its open position and said swingable side rails to the positions in which they form continuations of said fixed side rails.

15 13. In a machine as defined in claim 12 wherein said means for closing said first and second gate means, for shifting said platform and for swinging said swingable side rails to form continuations of said fixed side rails comprises a cam shaft with a cam for each thereof, and means for driving said cam shaft, and said initiating means includes means controlling the rotation of said cam shaft.
